TENT PEG EXTRACTOR OR THE LIKE

William A. Wood, Raleigh, N.C., assignor of a fractional
part interest to Everett D. Lassiter, Raleigh, N.C.

Filed Aug. 31, 1972, Ser. No. 285,319

Term of patent 14 years

Int. Cl. D8—05, 99

U.S. Cl. D8—88

FIG. 1

FIG. 2

FIG. 3

FIG. 4

FIG. 1 is a top perspective view of the tent peg extractor or the like showing my new design;

FIG. 2 is a side elevational view of the extractor;

FIG. 3 is an opposite side elevational view of the same;
and

FIG. 4 is a bottom perspective view of the extractor.

I claim:

The ornamental design for a tent peg extractor or the
like, as shown.
